UNITED STATES PATENT OFFICE.

ALBERT R. CHRISTMAN, OF PHILADELPHIA, PENNSYLVANIA, ASSIGNOR OF ONE-HALF
TO ELLIOT A. OBERRENDER, OF MELROSE PARK, PENNSYLVANIA.

REMOVING ADHERING MORTAR FROM BRICKS.

1,082,307.

Specification of Letters Patent. Patented Dec. 23, 1913.
Application filed May 2, 1913. Serial No. 765,042.

To all whom it may concern:

Be it known that I, ALBERT R. CHRISTMAN, a citizen of the United States, residing in Philadelphia, Pennsylvania, have invented 5 certain Improvements in Removing Adhering Mortar from Bricks, of which the following is a specification.

My invention relates to the cleaning of mortar from bricks, its objects being to facilitate and perfect the operation and to render such operation perfectly safe. These objects I attain in the manner hereinafter set forth, reference being had to the accompanying drawings, in which—

Figure 1 is a plan or top view of a machine for cleaning bricks in accordance with my invention; Fig. 2 is a side elevation of the same looking in the direction of the arrow *x*, Fig. 1; Figs. 3 and 4 are side elevations, on a larger scale, illustrating the operation of a certain die and ram whereby the preliminary cleaning of a portion of the brick is effected; Fig. 5 is a top view of said preliminary cleaning die and ram; Fig. 6 is a perspective view of the brick after the preliminary cleaning of the same has been effected; Fig. 7 is a longitudinal section of the main cleaning die illustrating also the manner of applying the partially cleaned brick thereto; Figs. 8, 9, 10 and 11 are diagrams illustrating in different relations to one another a certain cam and a lever for moving one of the sides of the final cleaning die, and Fig. 12 is a perspective view on a larger scale of said lever.

In Figs. 1 and 2 of the drawings, 1 represents the main frame, 2 a sliding plunger with a projecting ram 3, 4 a crank shaft, and 5 a connecting rod whereby the reciprocation of such plunger by means of said crank shaft is effected, all of these parts being common and therefore requiring no further or more detailed description.

Mounted upon the main frame, at one side of the machine, are three die plates 6, 7 and 8, the die plate 8 being vertical and the die plates 6 and 7 horizontal and disposed one above another and with their inner edges adjacent to the face of the die plate 8. The acting faces of all of the plates 45 6, 7 and 8 are toothed, as shown in Figs. 3, 4 and 5, and the upper horizontal plate 6

and the vertical plate 8 are fixed in position but the lower horizontal plate 7, is, by preference, pivoted at one end and acted upon by a spring 9 so that it can yield downwardly when the pressure of the spring is overcome, the extent of upward movement of said plate 7 being determined by the full expansion of the spring 9.

Projecting from one side of the plunger 2 through a suitable guide slot in the corresponding side of the machine frame is an arm 10 which carries a ram 11, the latter, on the back stroke of the plunger, being adapted to pass between the die plates 6 and 7 and in front of the die plate 8 at the side of the machine. The die plates 6 and 7 are relatively shallow but can receive between them a few inches of one end of the brick to be cleaned, and the acting faces 65 of said plates are tapered so as to be farther separated from one another at one end than at the other, as shown in Fig. 3. An attendant grasping an uncleared brick at one end can, therefore, without any risk of injury, place its opposite end between the die plates 6 and 7 and in front of the ram 11, as shown in Fig. 3, the front end of the brick bearing such relation to the face of the die plate 8 that, when the brick is thrust 70 by the advancing ram 11 between the plates 6 and 7 and across the face of the plate 8, the adhering mortar will be cleaned from the front end of the brick and also from the top and bottom faces of the brick for 75 a distance of an inch or more back from the front end, as shown in Figs. 5 and 6.

The finishing die 12 is carried by a slide 13 which is suitably guided on a transverse structure 14 at one end of the frame, reciprocating movement being imparted to this slide 90 at intervals by any suitable mechanism operating in conjunction with the plunger 2, this movement being such that at one of its terminations the die 12 will be in line with the 95 ram 3 of the plunger and at the other of its terminations said die will be at one side of the machine and out of the path of the plunger, as shown in Fig. 1.

The finishing die is composed of opposite 100 side plates 15, a bottom plate 16 and a top plate 17, the bottom plate 16 being rigid

but the top plate 17 being pivoted at the rear end and normally depressed by the action of a coiled spring 18, as shown in Fig. 7. The top plate 17 can, however, be raised, 5 when desired, against the pressure of the spring 18, the means employed in the present instance for this purpose being a rod 19 pivotally connected at its lower end to the die plate 17 and likewise connected at its 10 upper end to the forward arm of a lever 20 which is pivotally mounted upon a standard 21 projecting upwardly from the slide 13, as shown in Fig. 7.

As the slide 13 is moved back and forth, 15 the rear arm of the lever 20 is acted upon by a cam bar 22, fixedly mounted upon the top of the cross frame 14. The rear arm of the lever 20 has a hinged section 23 (Fig. 12) normally kept in line with the rest of 20 the arm by a spring 24 but capable of yielding upwardly when subjected to pressure from below.

The action of the cam bar upon the lever 20 is as follows, reference being had to Figs. 25 8, 9, 10 and 11: When the slide 13 is at that limit of its movement where the die 12 is in line with the ram 3 the lever 20 occupies the relation to the cam bar 22 shown in Fig. 8, that is to say, it is beyond the end of the 30 cam bar and its rear arm is below the under surface of the elevated end of said cam bar. As the die carrying slide 13 moves to the left, the lever 20 is carried beneath the cam bar 22, as shown in Fig. 9, and is acted upon 35 thereby so as to depress the rear arm of the lever and raise the forward arm of the same, thereby lifting the upper die plate 17. Said upper die plate is retained in the elevated position until the slide 13 has almost reached 40 the limit of its movement to the left, whereupon the rear arm of the lever 20 passes from under the cam bar 22, as shown in Fig. 10, and, being free to rise, permits the upper die plate 17 to be depressed by the 45 spring 18. On the movement of the slide 13 to the right the rear arm of the lever 20 passes over the top of the cam bar 22 and its pivoted member 23 is raised by contact with the elevated end of said cam bar, as 50 shown in Fig. 11, but when the lever passes beyond the cam bar, said pivoted member snaps back to its normal position so as to pass beneath the cam bar on the next movement of the slide 13 to the left.

55 Immediately in front of the die 12, when the latter is in the position shown in Fig. 1, is a rail or bar 26 which is flush with or slightly above the bottom plate 16 of the die. An attendant holding a partially cleaned 60 brick, such as shown in Fig. 6, may, therefore, rest the cleaned end of said brick on said bar so that said cleaned end will project beyond the bar and toward the die 12, this cleaned, projecting portion of the brick,

when the die 12 reaches the position shown 65 in Fig. 1, being between the forward ends of the lower and upper plates 16 and 17 of the die, as shown in Fig. 7.

As the die on its movement to the left approaches the brick the upper die plate 17 70 is raised so as to be free from contact with the upper face of the brick, but, just as the die reaches the limit of its movement, the lever 20 passes from under the influence of the cam bar 22 and the upper die plate 17 75 snaps down upon the top of the brick and securely confines said brick between the upper and lower plates of the die, whereby, as the die moves from the side of the machine toward the center of the same, it will carry 80 the partially cleaned brick with it, and will stop with the brick in line with the ram 3. When the ram advances, therefore, it will strike the rear end of the brick and will 85 strike the same through the die so as to remove the mortar from the right and left hand sides of the brick and complete the removal of the mortar from the top and bottom sides of the same.

It will be noted on reference to Fig. 7 90 that the top and bottom plates of the die 12 project beyond the side plates 15, consequently the presence of mortar up to the end of the brick on those sides which correspond with the side plates 15 of the die will not 95 interfere with the proper placing of the partially cleaned end of the brick between the upper and lower plates of the die.

If desired, a bar or rail 27 may be disposed above the rail 26 for contact with the 100 cleaned top face of the brick when the cleaned lower face of the same rests on said rail 26, thus serving to support the partially cleaned brick in position to be engaged by the top and bottom plates of the 105 die 12, even should the attendant let go of the brick before the die reaches the proper position to engage the same.

The machine is intended to be operated by two attendants one of whom, located at one 110 side of the machine, presents the bricks to the preliminary cleaning die and, after the partial cleaning of the brick, places it in position to be handled by the other attendant, located at the opposite side of the machine, the latter attendant presenting the partially cleaned brick in position to be clamped between the plates 16 and 17 of the finishing die 12. In neither case, however, 115 are the hands of the attendants brought into 120 position to be struck by a moving part of the machine, or caught between a fixed and a moving part of the same, and all risk of injury to either attendant is therefore overcome.

I claim:

The mode herein described of removing adhering mortar from bricks, said mode con-

sisting in first cleaning the mortar from opposite sides of the brick at and near one end of the same in order to prepare said brick for insertion between the jaws of a die, then inserting said partially cleaned sides of the brick between said jaws, and then driving the brick through said die.

In testimony whereof, I have signed my name to this specification, in the presence of two subscribing witnesses.

ALBERT R. CHRISTMAN.
